(62) Division of application No. 29/458,769, filed on Jun. 21, 2013, now Pat. No. Des. 738,487.

(57) **CLAIM**

(30) **Foreign Application Priority Data**

The ornamental design for a suction device for negative pressure therapy, as shown and described.

DESCRIPTION

Jan. 28, 2013 (EM) 002173476-0001
Jan. 28, 2013 (EM) 002173476-0002
Jan. 28, 2013 (EM) 002173476-0003
Jan. 28, 2013 (EM) 002173476-0004
Jan. 28, 2013 (EM) 002173476-0005

FIG. 1 is a perspective view of a suction device for negative pressure therapy showing our new design;
FIG. 2 is a top thereof;
FIG. 3 is a bottom view thereof;
FIG. 4 is a front view thereof;
FIG. 5 is a rear view thereof;
FIG. 6 is a right side view thereof; and,
FIG. 7 is a left side view thereof.
